CONTAINER

Christian H. Nelson, Lyndhurst, N. J.

Application April 30, 1937, Serial No. 139,855

4 Claims. (Cl. 132—82)

The invention relates to containers and more particularly to that type of containers designed to hold pulverulent materials as exemplified by face powders and the like, and has for its object to provide a simple container constructed in a novel manner to efficiently prevent spilling or leakage of the material. The invention contemplates further the provision of a novel container whereby the pulverulent materials contained therein may be dispensed in an economical and efficient manner for use as required. Other more specific objects will appear from the description herein-after and the features of novelty will be pointed out in the claims.

In the accompanying drawing, which illustrates several forms of the invention without defining its limits, Fig. 1 is a perspective view of the novel container with the cover removed; Fig. 2 is a perspective view of the interior section or receptacle of said container; Fig. 3 is a sectional elevation of the complete container, and Figs. 4, 5, 6, 7, and 8 are corresponding views showing different forms of the novel container.

In all of its preferred forms the container comprises a body section having an interior chamber for containing pulverulent material and provided with a relatively reduced dispensing opening dimensioned to predetermine the pulverulent material receiving area of an applicator when the latter is in position over said opening; the container further includes a movable closure section for said body section adapted to close the opening of said body section for the purpose of sealing the container when said movable closure section is in operative position on said body section.

As illustrated in Figs. 1, 2 and 3, the body section of the container consists of a carrier 10 and a receptacle 11 located within said carrier 10 and normally projecting outwardly beyond the same. The receptacle 11 constitutes the interior chamber of said body section and is provided in its upper portion with a relatively reduced dispensing opening 12 whereby communication is established with the interior of said receptacle 11 for the admission and removal of the contents; the latter, generally speaking, consists of pulverulent material as exemplified by face powder and the like. The carrier 10 may be of any convenient shape and dimensions and constructed of any suitable material dependent upon whether the container is to be discarded when empty or retained for further use; in the latter instance, the carrier 10 may be of ornamental form and character.

In the form being described, the movable closure section is exemplified by the cover 13

which is completely removable from and is designed to be telescopically fitted on the body section or more specifically on the carrier 10 to close the same and to engage the receptacle 11 and thereby seal the opening 12 thereof. The construction is such that the cover 13 telescopically engages the carrier 10 with sufficient friction to firmly fix said cover 13 in place thereon. With this arrangement, the top of the cover 13 will directly engage and be securely seated against the upper portion of the receptacle 11 and over the opening 12 thereof so that the latter is efficiently sealed to prevent escape of the contents of the container.

The receptacle 11 may be made of any suitable material and preferably is shaped and dimensioned to fit into the carrier 10 and to normally project outwardly beyond the same. In the preferred form, the receptacle 11 is resilient and is made for instance of rubber or other inherently resilient material; obviously the desired resilience in the receptacle 11 may be provided in other ways. In any case, the resilient receptacle 11 is normally expanded outwardly beyond the carrier 10 and accordingly will be engaged and compressed by the cover 13 when the latter is in position on the carrier 10. It will be clear as the cover 13 is forced down relatively to the carrier 10 that the receptacle 11 will thereby be placed under a resilient compression which forces the receptacle 11 into firm engagement with the cover 13 so that the opening 12 is efficiently sealed. It is to be understood that the frictional engagement of the cover 13 with the carrier 10 is generally sufficient to maintain the receptacle 11 in its compressed condition under resilient compression; if necessary or preferred, extraneous means of suitable type may be used to maintain the cover 13 against unintentional displacement by the tendency of the receptacle 11 to expand to its normal condition.

The container is designed primarily as a holder for face powder which, generally speaking, is applied, as required for toilet purposes, by means of an applicator such as is exemplified by the conventional so-called powder puff. When it is desired to utilize the powder the opening 12 may be covered with the powder puff and the body section then inverted so as to bring the face powder or other pulverulent material of the receptacle 11 into contact with that portion of said powder puff which is exposed to the interior of said receptacle 11 through said opening 12. If the receptacle 11 is resilient, as is preferred, it need not be inverted as stated above; in such

case, it is simply necessary to exert pressure upon the powder puff to compress said receptacle 11 and thereby develop a pressure gust within the same whereby the pulverulent material is expelled into contact with that portion of the powder puff which is accessible through the opening 12. By alternately exerting pressure upon the powder puff and relieving the same the resilient receptacle 11 may be caused to expel the desired quantity of the face powder into contact with the powder puff as set forth above. In this way the powder is dispensed without waste and yet an ample supply is applied to the powder puff for application thereby for instance to the face of the user. At the same time the container, when not in use, is efficiently sealed to protect the contents against contamination and to prevent spilling and leakage thereof.

In the form shown in Fig. 4, the cover 13^a is provided interiorly with means for increasing the sealing action thereof, said means being shown in the form of a sealing pad 14 permanently secured to the cover 13^a in position to register with and cover the opening 12^a of the receptacle 11^a. The sealing pad 14 may be of any suitable material such as rubber or the like, and in any case is of sufficient surface area to lie in surface engagement with the receptacle 11^a in peripheral proximity to and over the dispensing opening 12^a to thereby provide an adequate and efficient seal for said opening 12^a when the cover 13^a is in operative position on the carrier 10^a. Otherwise, the container may be constructed and operated in the same way as the form first described, it being understood that the receptacle 11^a preferably is resilient for the purposes set forth hereinbefore.

As constructed in Fig. 5, a tubular neck 15 projects from the receptacle 11^b for establishing communication with the interior thereof and for engagement with the cover 13^b when the latter is in operative position on the carrier 10^b; the internal dimensions of the neck 15 at its outer end are such as to provide a dispensing opening corresponding in character and function to the dispensing opening 12 of Fig. 1. To increase the sealing action and the co-operative efficiency of the cover 13^b and the neck 15, the latter may be provided with an annular flange 16 as shown in Fig. 5. In its preferred form the receptacle 11^b is also resilient and normally is expanded outwardly beyond the carrier 10^b so that the pressure of the cover 13^b on the neck 15 will place said receptacle 11^b under compression whereby the open end of said neck 15 is forced firmly against the top of the cover 13^b to effectively seal said receptacle 11^b against leakage or spilling. The construction of the container under discussion and its operation may otherwise be the same as in the previously described forms.

In the arrangement illustrated in Fig. 6, the receptacle 11^c may be substantially non-resilient or resilient, as preferred, and in any case may converge upwardly toward the relatively reduced dispensing opening 12^c, which corresponds to the opening 12 previously referred to. For the purpose of efficiently sealing the receptacle 11^c, the cover 13^c is provided interiorly with a recessed sealing member 14^c permanently secured in place and arranged to fit over the receptacle 11^c in peripheral proximity to and over the opening 12^c to efficiently close and seal the same when said cover 13^c is in operative position on the carrier 10^c, as shown in Fig. 6. The construction and operation of the container last described may

otherwise be the same as those previously referred to herein.

The container shown in Fig. 7 comprises a body section 10^d, the inside of which constitutes an interior chamber for containing pulverulent material; the body section 10^d includes a top 11^d provided with a dispensing opening 12^d whereby communication with the interior of the body section 10^d is established. The dispensing opening 12^d is of relatively reduced size and is dimensioned to predetermine the pulverulent material receiving area of an applicator as in the previous forms. The movable closure section of the form now being described comprises the cover 13^d and a sealing member 14^d permanently secured to the cover 13^d interiorly thereof; the sealing member 14^d is preferably recessed and adapted to engage the top 11^d in peripheral proximity to and over the opening 12^d when said cover 13^d is in place on the body section 10^d to cover and seal said opening 12^d. To increase the sealing efficiency, the sealing member 14^d is preferably resilient so as to engage the top 11^d under compression as will be apparent. In this form the face powder or other pulverulent material is contained in the interior chamber of the body section 10^d; the construction and operation otherwise may be the same as previously set forth herein.

In the form illustrated in Fig. 8, the container 11^e may be made of any suitable material adapted to hold the powder or its equivalent for which the container is designed, and includes an opening which registers with the opening 12^e of a neck member 15^e projecting from the receptacle 11^e and connected therewith in any convenient manner. The internal diameter of the neck member 15^e at its outer end is such as to provide a dispensing opening reduced relatively to the inside of the container 11^e and dimensioned to predetermine the pulverulent material receiving area of an applicator as in the preceding forms. Resiliency is imparted to the receptacle 11^e by one or more springs of suitable type and character. In the specific arrangement illustrated, the receptacle 11^e is provided with a plurality of springs shown in the form of leaf springs 16 of bow-like shape and arranged in transverse relation to each other and preferably covered on the inside by suitable material 17. With the arrangement under discussion, the movable closure section exemplified by the cover 13^e when in position on the carrier 10^e will engage the neck member 15^e and compress the receptacle 11^e against the tension of the spring 16 or their equivalent. The neck member 15^e will thereby be maintained in firm engagement with the top of the cover 13^e so that the opening 12^e will be closed and the receptacle 11^e will be efficiently sealed. Otherwise the form of container shown in Fig. 8 may correspond in construction and operation to those forms previously described herein. The receptacle 11^e, as illustrated in Fig. 8, is provided with an outwardly curved bottom whereby the compression of said receptacle by an applicator to effect the dispensing of the pulverulent material is facilitated. This feature may be embodied in the receptacles of Figs. 1 to 6 inclusive to provide an equivalent ejecting efficiency therein.

In all of those forms of the container which include the same, the receptacle such as 11 preferably converge toward the dispensing openings, for instance along externally convex lines as shown in Figs. 1 to 5 inclusive, and Fig. 8, 75

or along externally concave lines as illustrated in Fig. 6 to increase and facilitate the expelling compression thereof. Furthermore the various receptacles such as 11 may either be permanently combined with the carrier such as 10, or be removably located therein. In the latter instance, the receptacle such as 11 may be discarded when empty and replaced by a new filled receptacle; in other words, with such an arrangement the receptacle 11 and its equivalents constitute what may be termed "refills". In such case, suitable provision would be made to close the opening such as 12 in a manner to permit the seal to be easily broken when the receptacle has been inserted into the carrier.

In all of its forms the novel construction provides a container for face powder and other pulverulent material which is effectively sealed against spilling or leakage by simply placing the closure section in operative or closing position upon the body section. It will be understood that suitable provision is made in those forms in which the receptacle is resilient to maintain the cover in its closed position against unintentional disturbance by the resilient receptacle. This may be accomplished as in the illustrated examples by having the cover fit the carrier with a frictional engagement sufficient to resist the tendency of the compressed receptacle to expand to its normal condition. The carriers and covers of the container may be made of any customary material such as pasteboard and the like and discarded when empty, or these elements may be made in an ornamental form for permanent retention by the owner and for the periodic reception of successive receptacles such as 11.

The novel construction provides a container for face powder and other pulverulent material, which may be roughly handled without spilling the contents and which accordingly constitutes an ideal package for travelling; that is to say, the novel container may safely be stowed away in any convenient manner in the owner's baggage without danger of injury to the contents because of leakage or spilling of the pulverulent material from the container.

It is of course to be understood that any other type of cover may be substituted for the illustrated slidable and frictionally held covers, which are merely intended to exemplify the closure whereby the sealing of the containers is effected.

Various changes in the specific forms shown and described may be made within the scope of the claims without departing from the spirit of the invention.

I claim:

1. A receptacle for pulverulent material provided with a relatively reduced dispensing opening adapted to be temporarily covered by an applicator and dimensioned to define the pul-

verulent material receiving area thereof, said receptacle having an inherent resiliency whereby it may be compressed by said applicator to develop a pressure gust within said receptacle whereby the material therein is expelled into contact with that portion of said applicator which is accessible through said dispensing opening to the interior of said receptacle. 5

2. A receptacle for pulverulent material provided with a relatively reduced dispensing opening adapted to be temporarily covered by an applicator and dimensioned to define the pulverulent receiving area thereof, said receptacle being made of rubber having an inherent resiliency whereby said receptacle may be compressed by said applicator to develop a pressure gust within said receptacle whereby the material therein is expelled into contact with that portion of said applicator which is accessible through said opening to the interior of said receptacle. 10 15

3. The combination of a container having a normally open end, a receptacle for pulverulent material located within said container and provided with a relatively reduced dispensing opening at the normally open end of said container adapted to be temporarily covered by an applicator and dimensioned to define the pulverulent material receiving area thereof, said receptacle having an inherent resiliency enabling it to be compressed in said container to develop a pressure gust within said receptacle whereby the material therein is expelled into contact with that portion of said applicator which is accessible through said dispensing opening to the interior of said receptacle, and a movable cover for the open end of said container adapted in its closed position to engage said receptacle and place the same under a compression tension to thereby close and seal said dispensing opening. 30 35

4. The combination of a container having a normally open end, a receptacle for pulverulent material located within said container and provided with a relatively reduced dispensing opening at the normally open end of said container adapted to be temporarily covered by an applicator and dimensioned to define the pulverulent material receiving area thereof, said receptacle being made of rubber and having an inherent resiliency enabling it to be compressed in said container to develop a pressure gust within said receptacle whereby the material therein is expelled into contact with that portion of said applicator which is accessible through said dispensing opening to the interior of said receptacle, and a movable cover for the open end of said container adapted in its closed position to engage said receptacle and place the same under a compression tension to thereby close and seal said dispensing opening. 40 45 50 55

CHRISTIAN H. NELSON.
